UNITED STATES PATENT OFFICE

2,459,936

ROTARY VALVE FOR INTERNAL-COM-
BUSTION ENGINES

Robert H. Hasler, Old Westbury, and Harry P. Stevens, Oyster Bay, N. Y., assignors to The Hasler Stevens Corporation, Mineola, N. Y., a corporation of New York

Application January 15, 1948, Serial No. 2,455

4 Claims. (Cl. 123—80)

1

The invention herein disclosed relates to engines of the rotary valve type such as covered in Patent No. 1,249,235 issued to Harry P. Stevens.

The present improvements relate more particularly to the lubricating means for such engines of the nature disclosed in the copending patent application of Harry P. Stevens, Serial No. 787,354, filed November 21, 1947, in which the rotating valve discs are lubricated by pads of lubricant-carrying material located to engage the valve discs at points removed from the ports controlled by such discs.

Special purposes of the present invention are to provide efficient and fully satisfactory means for automatically applying proper pressure of the lubricating pads against the rotating valve discs.

Special objects are to assure that such necessary pressure will continue and be maintained so long as the engine is in operation.

Further special objects of the invention are to facilitate assembling and disassembling of the parts, and in particular to effect an automatic retraction of the oiling pads, thus to locate them out of the way of the valve structure in the assembling and disassembling operations.

Special objects of the invention also are to attain the objects described with a simpler form of construction and with fewer parts than were required before.

Another special object of the invention is to assure uniform functioning of all the lubricating parts in a multi-cylinder engine.

Other desirable objects attained by the invention are set forth or will appear in the course of the following specification.

The drawing accompanying and forming part of the specification illustrate a present practical embodiment of the invention, but it is to be understood that structure may be modified and changed as regards the immediate illustration, all within the true intent and broad scope of the invention as hereinafter defined and claimed.

Fig. 1 in the drawings is an enlarged broken vertical sectional view of portions of a cylinder block and cover with a rotary valve operating therein and having the lubricating features of the present invention incorporated, this view showing the tops of two of the engine cylinders and related valve structure;

Fig. 2 is a broken cross sectional view as on substantially the plane of line 2—2 of Fig. 1;

Fig. 3 is a broken longitudinal sectional view showing portions of the cylinder block and valve assembly, before applying the cover;

Fig. 4 is a similar view showing the cover re-

2

moved and in position to be lowered over the valve and cylinder block assembly.

The engine consists in general of a crank case and crank shaft, and a cylinder block and cover, with an overhead rotary valve having a shaft journaled between the block and cover.

In the drawings, the cylinder block 20 contains adjacent cylinders in line, such as 21 and 22 with their respective engine pistons 21' and 22'. The cover 23 is bolted to the block 20 by means of bolts such as 24, 24, with a water-tight gasket 25 clamped between the two members. Cooling water spaces such as 26, 26, 26 and 26, are shown.

The upper ends or heads of the cylinders 21 and 22 are extended to form, respectively, the narrow combustion chambers 27 and 28.

The cylinder block 20 contains semi-cylindrical spaces, such as 29, and the cover 23 contains complementary spaces such as 30, providing cylindrical spaces or chambers when the mating members 20 and 23 are bolted together.

The walls of the spaces in the block are integral with the combustion chamber walls and form continuations thereof. These walls are also integral with half round bearings such as 31, 31'.

The walls of the spaces in the cover are extended to form half round bearings such as 32, 32'.

When the cover member 23 is in place on the block 20, all the half round bearings form a row of complete bearings for the various sections, such as 33, 33', of the valve shaft.

The valve shaft sections connect and are integral with valve cages, the whole forming a valve shaft assembly.

This valve shaft assembly rotates between the block and cover. The cages do not contact the walls of the spaces but have a slight clearance. For a four-cycle engine, the shaft is driven at one-half crank shaft speed by suitable gearing, not shown.

Each valve cage consists of a pair of discs connected by a box-like hollow cell such as 34. For the purpose of light weight, the various cells are made hollow and the shaft sections tubular.

To simplify description, the valve cages are designated by a dual number, that of the two enclosing discs. Thus the cage shown in the central part of Figs. 1 and 3 is designated cage 35—36. These numbers also designate the respective discs. Other discs shown, or partially shown, are numbered 37 and 38.

Between the discs of each cage and outside of the cells is a gas space or channel such as 39 and 40.

Oppositely disposed ports such as 41 and 42 are provided in the vertical walls of each combustion chamber and these ports are in register periodically with elongated openings, such as 43 in the discs that communicate with the above mentioned gas channels in the cages. These channels, in turn, communicate with ducts such as 44 in the cylinder block. Thus, as the cages with their gas channels rotate, the inlet and exhaust gases pass to and from the combustion chambers in proper sequence.

Each combustion chamber port is provided with a gas-tight packing or seal ring in sliding contact with the adjacent disc. The discs and cylindrical walls of the cages rotate in the block recesses with a slight clearance as above stated, to avoid friction, and the seal rings are necessary to prevent the escape of gas around the cages.

Each seal ring illustrated consists of a bush such as 45 screwed into the wall of combustion chamber 27. The interior opening of this bush 45 forms the port 42.

A resilient annular diaphragm such as 46 is attached at its inner periphery to each bush and at its outer edge by means of a containing ring 48 to an antifriction contact ring 49. The spring pressure of the diaphragm maintains a gas-tight running contact of the ring with the disc.

A similar seal ring with its port 41 is located on the opposite wall of combustion chamber 21.

To more definitely follow the path of the gases through the valve structure, assume that the piston 21' is on its upward exhaust stroke in the cylinder 21. The exhaust gas from the cylinder escapes through combustion chamber 27 and port 42 and opening 43 in disc 35 into the gas channel 40 and then on out through duct 44 in the block 20.

The angular relationship of the elongated openings in the various discs is such that the inlet and exhaust gases are admitted to and discharged from the cylinders at such periods as to insure the correct timing of the engine.

Lubrication of the contact rings on the discs is accomplished with a series of porous oil pads located in recesses in the walls of the cover member. These pads are in running contact with the discs and are fed from a system of pipes that carry oil through the cover from a suitable source.

The pads not only supply oil, but they distribute it over a large surface of the discs in the path of the contact rings and in the exact minute quantities required. These pads may be made of sintered metal, carbon or any oil-impregnated porous bearing material.

The engine and its parts thus far described are similar to the showing in the above-mentioned pending patent application, Serial No. 787,354.

The present invention concerns the construction, assemblage and operation of the porous lubricating pads.

Each pad such as 50, is supported by a shell 51 made of solid metal. The outer edge of this shell is spun or crimped over the outer edge of the porous pad, as shown. Both the pad and shell are positioned within a circular recess 52 in the wall of the cover 23. This recess is slightly larger in diameter than the shell to permit clearance. It is also considerably wider than the combined width or depth of the shell and pad to afford clearance for substantial longitudinal movement of the shell.

The shell is integral with or mounted on a 75

cylindrical portion or piston 53 that is free to slide in a longitudinal cylindrical opening 54 through the cover member. This opening is intercepted and crossed by an oil tube 55 that extends to the bearing 32. This oil tube 55 is connected to a cross tube 56 which in turn connects with a feeder tube 57 that runs the length of the cover and feeds similar tubes that carry oil to the other porous pads associated with the valve parts of the other cylinders of the engine. This feeder tube 57 is supplied from an oil pump, not shown, driven by the engine in usual conventional manner.

Lubricating oil under pressure enters the opening 54 and flows through an oil hole 58 in the piston 53 and into a reservoir 59 between the shell 51 and the pad 50. From there it seeps in minute quantities through the pad over the surface of the disc 35.

No springs are required to press the pads against the discs, the pressure being created by the oil in the openings 54. As this pressure is the same in all similar openings, the pressure of all the oil pads on all the discs of the engine will be uniform.

To assemble the engine parts, the valve shaft assembly is placed in the top of the engine cylinder block, as shown in Fig. 3. The shells containing the porous oiling pads are put in place 30 in the cover, as shown in Fig. 4. As they are free to slide longitudinally over a substantial distance in their recesses, they may be manually pushed back to the positions shown in Fig. 4. In this position, the distance separating opposite 35 pads 50 and 50' is considerably larger than the width of the cage 35-36. Consequently, when the cover 23 is let down on the valve assembly, to be bolted in place on the block 20, the porous pads are back in their recesses and out of the 40 way so as not to interfere with easy assembling of the cover on the block.

To prevent the escape of oil around the pistons 53 into recesses 52, annular elastic, resilient packing rings such as 60 are placed in annular grooves 61 in the pistons. These rings may be stretched over the pistons and snapped into their grooves. They are resistant to temperature and oil and form effective seals to prevent leakage of oil.

It will be seen that the shell and piston parts 51 and 53 with pad 50, may be readily slipped into place in the cover by hand without the use of tools. This is of importance considering their 55 inaccessible location in the cover. They may also be readily drawn out by hand and this feature is also of advantage, since it would be impossible or difficult to manipulate a pulling tool in such inaccessible location.

The use of tools of any kind in assembling and disassembling these parts is not advisable because of the fragile nature of the porous pad material.

After the cover has been bolted to the block as above described, and the engine has been started, the oil pressure will build up back of the pistons and the porous pads be immediately pressed against the discs to begin functioning as oil distributors. On release or reduction of pressure when the engine stops, the pistons carrying the pads will retract, relieving the valve discs of pressure and automatically stopping any feed of oil. The structure is simple and rugged and the parts are few and can be produced and assembled at low cost. The hollow shell enlargements at the outer ends of the pistons, as shown in Fig. 4, may operate as stops engageable with the walls at the

back of the recesses 52 to limit the retractive movements of the pistons and hence keep them sufficiently spaced apart for entry of oil between them.

What is claimed is:

1. In an engine having a cylinder block, a cover for said cylinder block and a valve shaft rotating between said block and cover and having valve discs in cooperative relation with the cylinders, said block and cover having cylindrical chambers in which the valve discs rotate, lubricating pads for said valve discs, pressure responsive means movably supporting said pads in the cover in position for engagement with and disengagement from the faces of said valve discs, the movement of the pads away from the valve discs being sufficient to carry the lubricating faces of the pads below the surfaces defining the walls of the cylindrical valve chambers in the cover whereby said lubricating pads may be retracted below the valve chamber defining walls when the cover is applied to the block over the valve discs and means carried by the cover for applying fluid under pressure to said pressure responsive means for projecting the pads, when the cover is in place on the block, into lubricating engagement with the faces of the valve discs.

2. In an engine having a cylinder block, a removable cover and a valve shaft operating between said block and cover and carrying valve discs cooperating with the cylinders in the block, said cover having cylinder bores therein parallel to the axis of the valve shaft and located between valve discs of adjoining cylinders, oppositely operating pistons in said bores, lubricating pads at the outer ends of said pistons in opposition to the valve discs at the opposite ends of said bores, said pistons having retractive movement to enable complete clearance of the lubricating pads from the valve discs and oil supply passages extending into the bores between the pistons to admit oil under pressure for forcing the pistons apart to carry the pads into engagement with the valve discs.

3. In an engine having a cylinder block, a removable cover and a valve shaft operating between said block and cover and carrying valve discs cooperating with the cylinders in the block, said cover having cylinder bores therein parallel to the axis of the valve shaft and located between valve discs of adjoining cylinders, oppositely operating pistons in said bores, lubricating pads at

the outer ends of said pistons in opposition to the valve discs at the opposite ends of said bores, said pistons having retractive movement to enable complete clearance of the lubricating pads from the valve discs and oil supply passages extending into the bores between the pistons to admit oil under pressure for forcing the pistons apart to carry the pads into engagement with the valve discs, said pistons having oil supply passages therethrough and the pads at the outer ends of the pistons being of porous structure to pass lubricant through the same to the faces of the valve discs.

4. In an engine having a cylinder block, a removable cover and a valve shaft operating between said block and cover and carrying valve discs cooperating with the cylinders in the block, said cover having cylinder bores therein parallel to the axis of the valve shaft and located between valve discs of adjoining cylinders, oppositely operating pistons in said bores, lubricating pads at the outer ends of said pistons in opposition to the valve discs at the opposite ends of said bores, said pistons having retractive movement to enable complete clearance of the lubricating pads from the valve discs and oil supply passages extending into the bores between the pistons to admit oil under pressure for forcing the pistons apart to carry the pads into engagement with the valve discs, the cylinder block and cover having bearings for the valve shaft, said oil supply passages extending between the inner end of opposed pistons to said bearings and the inward movement of companion pistons in the same bore being limited to prevent said pistons from cutting off supply of oil in between said pistons and continuing said flow of oil to said valve shaft bearings.
